UNITED STATES PATENT OFFICE

157,630

AUTOMOBILE AIR DEFLECTOR

Linus E. Russell, Springfield, Ohio, assignor to
 Peters & Russell, Inc., Springfield, Ohio, a corporation of Ohio

Application April 14, 1949, Serial No. 1,983

Term of patent 14 years

(Cl. D14—6)

To all whom it may concern:

Be it known that I, Linus E. Russell, a citizen of the United States, residing at Springfield, Clark County, Ohio, have invented a new, original, and ornamental Design for an Automobile Air Deflector, of which the following is a specification, reference being had to the accompanying drawing, forming a part thereof, in which—

Fig. 1 is a perspective view of an automobile air deflector embodying my new design;

Fig. 2 is an end or bottom view thereof;

Fig. 3 is a front view thereof, and

Fig. 4 is a sectional view on line 4—4 of Fig. 2.

The characteristic features of my design reside in the portions shown by means of full lines in the drawing.

I claim:

The ornamental design for an automobile air deflector, substantially as shown and described.

LINUS E. RUSSELL.
